DESIGN FOR A BELT FOR PERSONAL WEAR

Daniel T. Manning, Rochester, N. Y., assignor to Hickok Manufacturing Company, Inc., Rochester, N. Y., a corporation of New York

Application January 30, 1936, Serial No. 60,903

Term of patent 3½ years

To all whom it may concern:

Be it known that I, Daniel T. Manning, a citizen of the United States, residing at Rochester, in the county of Monroe and State of New York, have invented a new, original, and ornamental Design for Belts for Personal Wear, of which the following is a specification, reference being had to the accompanying drawing, forming part thereof.

Fig. 1 is a perspective view of a belt for personal wear showing one adaptation of my new design; the detailed illustration of the belt being continued throughout the length of the belt, the shaded lines denoting contrasting color; and

Fig. 2 is a view of a portion of the belt shown in Fig. 1 on an enlarged scale.

The dominant feature of the present design resides in the plurality of the central longitudinally disposed connected cords which are unconnected at intervals adjacent the buckle engaging end, as shown.

I claim:

The ornamental design for a belt for personal wear as shown and described.

DANIEL T. MANNING.
